Primary Examiner — Philip S Hyder*Assistant Examiner* — Cary M Robinson(74) *Attorney, Agent, or Firm* — Wolf, Greenfield & Sacks, P.C.(57) **CLAIM**

The ornamental design for a display screen with transitional graphical user interface, as shown and described.

DESCRIPTION

FIG. 1 is the first image in a sequence for a display screen with transitional graphical user interface showing my new design;

FIG. 2 is the second image thereof;

FIG. 3 is the third image thereof;

FIG. 4 is the fourth image thereof; and,

FIG. 5 is the fifth image thereof.

The broken line at the periphery of the figure illustrates a display screen, and the remainder of the broken lines illustrate portions of the transitional graphical user interface. None of the broken lines form part of the claimed design. The appearance of the image transitions sequentially between the images as shown in FIGS. 1 through 5. The process or period in which an image changes into another image forms no part of the claimed design.
